APPARATUS FOR TREATING MATERIALS

William L. Wettkaufer, Buffalo, N. Y.

Application January 22, 1935, Serial No. 2,913

Renewed October 12, 1937

4 Claims. (Cl. 210—68)

This invention relates to an apparatus for use in the treatment of coal and other granular substances and particularly for the purpose of separating water, silt and like fine foreign matter from the solid particles.

It has for its chief object to provide an efficient apparatus of this character which is designed to handle a maximum tonnage in a minimum period of time and with a minimum expenditure of power, and which effectually and thoroughly extracts the water as well as the silt and other fines from the solid material.

Another object of the invention is the provision of a de-watering apparatus for coal and like substances which is simple, compact and sturdy in construction, which is continuous in operation, and wherein the separating unit of the apparatus is self-cleaning.

Other features of the invention reside in the construction and arrangement of parts herein-after described and particularly pointed out in the appended claims.

In the accompanying drawings:

Figure 1 is a sectional side elevation of the separating apparatus embodying my invention. Figure 2 is a sectional top plan view thereof. Figure 3 is an enlarged central vertical section of the centrifugal separating drum of the apparatus. Figure 4 is a fragmentary horizontal section taken on line 4—4, Figure 3.

Similar characters of reference indicate corresponding parts throughout the several views.

Referring now to the drawings, 10 indicates a supporting frame or member upon which is mounted a driving unit which is preferably in the form of an electric motor 11 having its shaft 12 disposed in an upright position for rotating the revolvable or centrifugal element of the separating or de-watering apparatus.

The revolving element of the apparatus, which functions by centrifugal force to extract the water as well as the silt from the coal or other substance being treated, preferably consists of a substantially conical-shaped, foraminous sieve-like member or drum 13 overhanging the motor 11 and suitably secured to the shaft 12 thereof to be driven thereby at a comparatively high speed. This centrifugal drum or casing is open at its top and bottom and is stepped to provide a plurality of annular separating zones 13a of successively increasing surface area or diameter from the top or feed end to the bottom or discharge end of the drum and each zone being inclined downwardly and outwardly in the manner shown in Figures 2 and 3. This drum includes

a skeleton-like internal frame composed of longitudinal ribs or flanges 14 which project radially inward from the inner sides of the drum and which are laterally offset, as indicated at 15, to follow the contour of the stepped separating zones 13a. Aside from constituting strengthening means for the drum, these flanges, which are suitably spaced radially, form resulting channels or compartments for the downward flow of the material being treated and afford an even distribution of the material over the separating zones as the drum is revolved. Also constituting a part for the reinforcement of the drum as well as deflecting walls for intercepting and directing the material from one separating zone to another, 16 are superposed transverse members 16, 17 and 18 which are preferably in the form of circular plates or baffles and which are in edgewise spaced relation to the inner surface of the drum and are anchored at their peripheries, by welding or otherwise, to the opposing edges of the flanges 14, thereby leaving a path of flow for the material along the inner wall of the drum during the de-watering operation. The uppermost baffle plate 16 is disposed immediately below the feed-end or mouth 19 of the drum, while the subjacent pairs of baffle plates 17, 18 are disposed in a plane adjoining the respective offset portions 15 of the flanges 14, whereby the material during its downward flow through the drum is intercepted at predetermined points and deflected outwardly as it passes from one separating zone into another. One of the plates 17 or 18 is provided with an attaching collar 20 for connecting the drum to the motor-shaft 12.

While the annular separating zones 13a of the drum may be made of screening or other foraminous material, I have shown them made from sheet material having slots 21 therein for the discharge of water, silt and like matter to be separated from the substance undergoing treatment. By preference, these slots are obliquely disposed in a direction counter to the direction of rotation of the drum to effect a more positive separation and escapement of the minus material from the aggregate as it is fed downwardly along the inside face of the drum.

Mounted in spaced relation over the drum 13 is a hood 22 which is supported from the frame member 10 by braces 23 and which is provided at its lower end with an inwardly-disposed trough or collecting sump 24 for the water and silt removed from the coal, this trough having a discharge opening 25 therein communicating with a spout 26 for directing separated matter 55

to a point away from the apparatus. At its upper end this hood has a feed hopper 27 into which the material to be treated is delivered and from which it is discharged by gravity into the feed-end 19 of the drum 13. If desired, the lower end of the latter may be provided with a trough 28 for receiving any surplus water extracted from the material and which flows down the outer surface of the drum. The outer wall of this trough 10 is deflected outwardly and extends to a point at or above the hood-trough 24 to thereby direct the extracted water outwardly and upwardly by centrifugal force against the hood and thence into its trough.

15 Briefly stated the operation of the apparatus is as follows:—

The material to be treated is delivered to the hopper 27 from which it flows by gravity into the feed-end 19 of the revolving separating drum 20 13, centrifugal force directing and impinging the material against the inner wall of the drum and gravity causing the material to flow downwardly along the stepped separating zones 13a. In flowing continuously through the separating drum 25 in this manner, the material is distributed uniformly between the radial flanges 14 and as it passes downwardly from one separating zone to another it is distributed over a resulting larger surface area and thinned out, thereby obtaining a thorough and maximum separation and de-watering of the material. The water and fines, such as the silt and other foreign material, are thrown outwardly and extracted from the aggregate and pass through the drum-slots 21 against 30 the hood 22, being ultimately delivered to the trough 24 from which they are drained or discharged through the spout 26, while the dried material or aggregate flows by gravity and is discharged from the lower end of the drum where 35 it may be delivered to a suitable bin or receptacle for receiving it. In flowing downwardly through the drum from one separating zone to another, the material impinges against the baffle-plates 16, 17 and 18 and then is directed outwardly therefrom by centrifugal force against the drum-walls. If desired and the material requires it, it may be passed through two or more separating units of like construction until the proper separation and de-watering has been effected.

50 I claim as my invention:—

1. In a material treating apparatus of the character described, a centrifugal separating drum open at its upper and lower ends for the feed and discharge of material to and from the same, flanges disposed substantially radially about said drum and extending inwardly from the walls thereof, and baffle means disposed within said drum in superposed spaced relation to provide a plurality of separating zones, said baffle means abutting at their peripheries with the opposing edges of said flanges and adapted to

5 intercept and direct the material outwardly from the lower end of one zone to the upper end of an adjoining zone, said drum having discharge slots in the zone areas thereof for the discharge of water and like matter separated from the material undergoing treatment.

2. In a material treating apparatus of the character described, a centrifugal separating drum open at its upper and lower ends for the feed and discharge of the material to and from the same, said drum being stepped along its side wall to provide a plurality of separating zones therein along which the material is adapted to flow, and means disposed within the drum and in planes adjoining the stepped portions thereof for intercepting the material and directing it from one zone to another, the drum-walls at the separating zones having discharge slots therein disposed obliquely in a direction counter to that of the drum-rotation and with their leading ends 15 disposed at the upper ends of the slots.

3. In a material treating apparatus of the character described, a centrifugal separating drum open at its upper and lower ends for the feed and discharge of the material to and from the same, said drum being stepped along its side wall to provide a plurality of separating zones therein along which the material is adapted to flow, the drum-walls at the separating zones having discharge slots therein disposed obliquely in 25 annular rows about the drum with the leading ends thereof constituting the upper ends of the slots, flanges disposed substantially radially about said separating zones and extending inwardly from the walls thereof, and baffle means disposed in the path of flow of the material and adjacent the junction of the several zones for intercepting and directing the material outwardly from the lower end of one zone to the upper end of an adjoining zone, said baffle means 30 terminating at their outer edges in substantially abutting relation to the inner edges of said flanges.

4. In a material treating apparatus of the character described, a centrifugal separating drum open at its upper and lower ends for the feed and discharge of the material to and from the same, said drum being stepped along its side wall to provide a plurality of separating zones therein along which the material is adapted to flow, flanges disposed substantially radially about said separating zones and extending inwardly from the walls thereof, and baffle means disposed in the path of flow of the material and adjacent the junction of the several zones for intercepting and directing the material outwardly from the lower end of one zone to the upper end of an adjoining zone, said baffle means terminating at their outer edges in substantially abutting relation to the inner edges of said flanges.
